Attorneys.

UNITED STATES PATENT OFFICE.

GEORGE A. NEWMAN, OF ST. PAUL, MINNESOTA.

PROCESS OF DECORATING WALLS.

Application filed December 30, 1924. Serial No. 758,945.

My invention relates to process of decorating walls and an object is to provide a process which is much more expeditious and convenient than the customary method of 5 stencilling patterns upon walls. My process broadly considered consists in providing a sheet of paper or other flexible material having any desired pattern thereon in relief, applying paint of any desired color 10 to said pattern and pressing said pattern with the paint thereon in wet condition upon successive portions of the wall.

The full objects and advantages of my invention will appear in connection with the 15 detailed description thereof and the novel features embodied in my inventive idea will be particularly pointed out in the claim.

In the accompanying drawing, which illustrates the steps in my process,—
20 Fig. 1 is a face view showing a fragment of an unpainted wall. Fig. 2 is a face view showing the fragment of the wall painted for a background. Fig. 3 is a face view showing the fragment of the wall painted 25 with a pattern over the background. Fig. 4 is an enlarged sectional view of a sheet of paper having a pattern in relief thereon. Fig. 5 is an enlarged sectional view of a border-like piece of paper having a pattern 30 in relief thereon.

In carrying out my process a wall designated at 10 in Fig. 1 is first preferably painted with any desired color to form a background. In case the wall is already painted 35 with a suitable color to constitute a background, it may suffice to clean the wall without applying a new background coat. The background is indicated at 12 in Fig. 2, the color being shown as yellow for illustrative 40 purposes. After the background coat has been applied it is allowed to dry before proceeding with the rest of my process. For this purpose I provide heavy sheets of paper 45 or other flexible material having patterns thereon in relief. In Fig. 4 raised portions which form the pattern are indicated at 14, this paper being intended for use in imparting 50 a pattern to the main portion of the wall. In Fig. 5 raised portions which form the pattern are indicated at 16, this paper being intended for use in imparting a pattern 55 to the border portion of the wall. After

the background coat has become dry, or the wall has been cleaned, a sheet of paper such as that shown in Fig. 4 is utilized by applying paint to the pattern thereon, such paint being of any suitable color which will harmonize with the background color. The paper carrying the paint in wet condition is then pressed down over successive portions 60 of the wall and the pattern of the raised portions is thereby reproduced upon the background coat. The paper may be of any suitable size which is convenient for handling, and it is pressed down upon successive portions of the wall until the entire surface is covered with the pattern. Additional paint is applied to the pattern paper from time to time, as necessary, to impart the proper amount of paint. In order that the 65 pattern may be properly positioned on the wall, the paper is oiled or otherwise made translucent or the material may originally be translucent in order that the underlying surface of the wall may be seen therethrough. As shown in Fig. 3, the paint for the pattern is indicated as being blue, although it will be understood that any desired color may be used. In this figure the main pattern is indicated at 18 and the border pattern at 20. It will be obvious that if desired, different colored paints may be used 70 for the main and border patterns. Any heavy paper, or other flexible material having a raised portion thereon, may be used. In practice, heavy wall paper having a pattern in relief of the same absorbent material as the paper has been found to be very effective.

I claim:

The process of decorating walls which consists in providing a sheet of flexible absorbent material having a pattern thereon in relief of the same absorbent material as said sheet treating said material to render it translucent, applying paint to said pattern, pressing said pattern while the paint thereon is still wet upon successive portions of the wall, and applying additional paint to said pattern from time to time as required to impart the proper amount of paint to the wall.

In testimony whereof I hereunto affix my signature.

GEORGE A. NEWMAN.
